UNITED STATES PATENT OFFICE.

EARL ELWIN BERRY, OF BELOIT, WISCONSIN, ASSIGNOR TO BELOIT IRON WORKS, OF BELOIT, WISCONSIN, A CORPORATION OF WISCONSIN.

PAPER-MAKING MACHINE.

Application filed April 10, 1924. Serial No. 705,429.

This invention relates to a paper making machine and more particularly to the breast roll end of a Fourdrinier having a traveling apron associated with the breast roll and with the wire and adapted to be shaken therewith by any suitable means, so that the pulp which flows on to the traveling wire at the same speed of the wire or nearly so, will not be permitted to filter until the fibres are thoroughly crossed or interlaced and have passed the traveling apron.

It is an object of this invention to provide the breast roll end of a Fourdrinier machine with a traveling apron adapted to prevent pulp filtration from taking place until after the pulp has been thoroughly shaken to cause interlacing of the fibres.

It is also an object of the invention to provide a paper making machine wherein the pulp is passed on to the wire above an endless apron which is engaged around the breast roll within the bight of the wire.

It is a further object of the invention to provide a paper making machine having a movable apron beneath the wire so that it will be possible to produce a sheet of paper with a much finer formation and with the fibres thoroughly interlaced to provide a sheet of paper of substantially equal strength in all directions.

It is furthermore an object of the invention to provide a paper making machine wherein a film of pulp on the wire is thoroughly shaken before any filtration or formation takes place and without requiring the use of a slice before the pulp enters on the formation area of the wire.

It is an important object of this invention to provide a paper making machine of improved construction having a set of table rolls independent of the regular table rolls adapted to support a traveling apron between the laps of the wire with the traveling apron also passing around the breast roll within the bight of said wire.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary side elevation of the breast roll end of a Fourdrinier paper

making machine embodying the principles of this invention.

Figure 2 is an enlarged fragmentary transverse section taken on line 2—2 of Figure 1.

Figure 3 is an enlarged fragmentary detail section taken on line 3—3 of Figure 2.

As shown on the drawings:

The reference numeral 1 indicates a paper making machine head box or flow box provided with a stationary apron 2 and with a slice 3 which is adapted for varying the thickness of the sheet to be formed. The flow box 1 is supported upon base rails 4. Secured to the base rails and to the sides of the flow box 1 respectively are flexible supporting springs 5 and 6 which support bearings 7 for a breast roll 8.

Mounted on the base rails 4 are a plurality of upright supports or pedestals 9 and 10. Mounted on the top of the uprights 9 are extension arms 11. Deckle bars 12 are supported upon the tops of the arms 11 on each side of the machine and support the deckle rails 13. Deckle straps 14 are trained around deckle pulleys 15. Also mounted upon each of the uprights 9 to the inside of the arms 11 are pairs of upright wooden springs 16. Similar pairs of wooden springs 16 are also mounted upon the tops of the uprights 10. Bolted to the tops of the springs 16 are table roll rails 17. A plurality of table roll bearings 18 are mounted upon the table rails 17 and are equipped with adjusting mechanisms 18a. Rotatably supported in bearings on the table roll rails 17 is an apron roll 19 around which an endless traveling apron 20 is trained. The traveling apron 20 is also trained around the breast roll 8 and runs over an apron guide roll 21 supported between a pair of the uprights 9.

Rotatably supported in the bearings 18 between the breast roll 8 and the apron roll 19 are a plurality of apron table rolls 22 over which the upper lap of the traveling apron runs. Table rolls 23 similar in construction to the rolls 22 are supported in the bearings 18 which are located beyond the apron roll 19. Engaged around the breast roll to the outside of the travel apron 20 is the Fourdrinier wire 24 which continues over the upper lap of said apron 20 and then travels over the table rolls 23 and returns over guide rolls 25.

A spray pipe 26 is provided adjacent the

apron roll 19 so that a spray of water may be directed on the traveling apron 20 for the purpose of washing it before it returns to the breast roll. A doctor 27 is supported 5 on the base rails and has mounted thereon a flexible strip of material 28, such as rubber. The strip of material 28 acts as a scraper against the lower lap of the traveling apron to remove any fibres that may be 10 clinging to the traveling apron and have a tendency to make an uneven surface.

The operation is as follows:—

The paper making machine of this invention covers a Fourdrinier section of substantially 15 typical construction having improved features, the most important being the traveling apron arrangement which is provided so that a strong sheet of paper may be made which is strong in both directions.

20 The machine may be driven from any suitable source of power and a shaker mechanism of any desired type may be connected to impart the necessary shake to the breast roll and to the table rails and rolls.

25 Pulp is permitted to flow from between the stationary apron 2 and the slice 3 on to the wire 24 at a velocity a little slower than the speed of the wire, in order that the wire can pick it up at a velocity equal to the speed 30 of said wire.

The traveling apron 20 runs over the breast roll, the rolls 22 and the apron roll 19 within the bight at one end of the wire 24, and said traveling apron acts to prevent any 35 filtration or formation of the sheet taking place during the period that the pulp is being shaken on the wire between the breast roll 8 and the apron roll 19. The fibres in the pulp are thus thoroughly crossed or 40 closely interlaced before the pulp is carried over the traveling apron 20 by the wire over onto the table rolls where filtration begins to take place. With the fibres thoroughly interlaced and the pulp traveling along at

the same speed as the wire the fibres will 45 settle down in their relative positions as filtration starts.

By using the improved traveling apron in the Fourdrinier the pulp is well shaken and the fibres thoroughly interlaced before any 50 formation is permitted to take place due to filtration through the wire. The use of an additional slice is also obviated and there is therefore no tendency to disarrange the fibres after they have been properly interlaced as described. A sheet of paper of much finer formation is thus formed, said paper having a more equal strength in each 55 direction.

The shaken pulp is carried by the wire 60 over the apron roll 19 and over the table rolls 23. As the traveling apron 20 passes around the roll 19 water is sprayed from the spray pipe 26 into the traveling apron to wash the same before it returns to the 65 breast roll. The flexible strip 28 on the doctor 27 serves to scrape the washed traveling apron so that all fibres are removed.

I am aware that many changes may be made, and numerous details of construction 70 may be varied through a wide range without departing from the principles of this invention, and I therefore do not purpose limiting the patent granted hereon, otherwise than necessitated by the prior art. 75

I claim as my invention:—

In a Fourdrinier paper machine adapted for making a continuous web of paper and having a shaking mechanism, the combination with the breast roll and a plurality of 80 table rolls, of an impermeable endless apron mounted for movement thereover, said apron extending a substantial distance beyond the slices to form a pond of stock subject to the shaking action. 85

In testimony whereof I have hereunto subscribed my name.

EARL ELWIN BERRY.
